DRY CLEANING UNIT

Daniel E. Beduhn, Manitowoc, Wis., assignor to Manitowoc Engineering Corporation, Manitowoc, Wis., a corporation of Wisconsin

Filed Aug. 14, 1961, Ser. No. 66,340

Term of patent 14 years

(Cl. D49—1)

FIGURE 1 is a perspective view of a dry cleaning unit showing my new design;

FIGURE 2 is a front elevational view thereof;

FIGURE 3 is a side elevational view thereof;

References Cited in the file of this patent

Home Furnishings Daily, Sec. 2, p. 8, February 20, 1961, RCA Whirlpool.

Mart, July 1960, page 73, Amana Freezer-plus-refrigerator.

The Whirlpool Miracle Kitchen, Whirlpool Corp., St. Joseph, Mich., rec'd May 27, 1957, page 11, lower right-hand corner.

FIGURE 4 is a rear elevational view thereof, and
FIGURE 5 is an enlarged fragmentary perspective view thereof, showing the control panel in detail.

The side not shown is substantially the same as the side shown.

I claim:

The ornamental design for a dry cleaning unit, substantially as shown and described.
